UNITED STATES PATENT OFFICE

GUSTAVE WALTER, OF JERSEY CITY, NEW JERSEY

LOCOMOTIVE BELL RINGER

Application filed January 17, 1930. Serial No. 421,565.

The present invention relates to improvements in locomotive bell ringers, and has for an object to provide a simply constructed and a simply operating locomotive bell ringer of

5 a compact construction adapted to be actuated by air under pressure or other elastic fluid.

Another object of the invention is to provide an improved locomotive bell ringer that 10 will insure the operation of the bell and will avoid the hammering of the plunger within the cylinder of the bell ringer.

With the foregoing and other objects in view, the invention will be more fully described hereinafter, and will be more particularly pointed out in the claims appended hereto.

In the drawings, wherein like symbols refer to like or corresponding parts throughout 20 the several views,

Figure 1 is a longitudinal sectional view taken through an improved bell ringer constructed in accordance with the present invention.

25 Figure 2 is a similar view with parts broken away and showing the device in a subsequent position, and

Figure 3 is also a longitudinal fragmentary sectional view with the parts in a third position of operation.

Referring more particularly to the drawings 5 designates the cylinder or barrel of the motor and 6 represents the plunger or piston mounted to reciprocate within the cylinder 5, the plunger 6 being coupled to the plunger rod 7 which extends through one head of the cylinder and is adapted to be coupled to the bell as hereinafter explained.

The other end of the cylinder 5 is open 40 and there is fitted to such open end a valve casing 8 having a flange 9 for fitting within the cylinder. This casing 8 is secured to the cylinder as by the use of bolts or other fastening means 10. The casing 8 is traversed by a transverse passage 11, which runs from end to end of the casing 8 and crosswise of the cylinder 5. This passage 11 is constructed of differential diameters with a valve seat 12 between the portions of greater and less diameter. This valve seat 12 is adapted to co-

operate with a reciprocating valve 13 carried on a valve stem 14 which is fitted to slide snugly within the part of the passage 11 having the smaller diameter.

The stem 14 is of such length that it will 55 project from the passage 11 and at its projecting end it is preferably provided with a rounded nose for a purpose later explained. At an intermediate point, the stem 14 is provided with a reduced part 15 for forming an 60 annular channel about such reduced part and within the passage 11, whereby the compressed air or other elastic fluid, which is received through the inlet 15 from an appropriate source into the larger portion of the passage 11 may flow past the valve 13 and through the inlet port 17 into the interior space of the cylinder 5 at one side of the plunger 6. The valve 13 is normally and yieldably held to its seat by the action of a 65 coil spring 18. The valve and its valve stem and the coil spring are inserted through the larger end of the passage 11, after which the valve assembly and spring is held in place by a threaded plug 19, which is also useful 70 in adjusting the tension of the spring 18.

The cylinder 5 adjacent but in spaced relation from its closed end is provided with an air outlet indicated at 20. The cylinder 5 carries at one side a guide-way 21 for a valve 80 rod 22, which is mounted to reciprocate in the guide and through a stuffing box 23 mounted in one end of the guide-way 21.

The cylinder 5 near the inlet end and the guide-way 21 are provided with registering 85 exhaust ports 24. The valve rod 22 carries a reduced free end 25 and a beveled nose 26 for encountering the projecting rounded end of the valve stem 14.

Spaced adjusting nuts 27 and 28 are mounted on the screw threaded end of the valve rod 22 and are held in adjusted position by the companion lock nuts 29 and 30. The eye 29' of a bolt 30 is adapted to loosely fit over the threaded portion of the valve rod 22 and to slide back and forth between the adjusting nuts 27 and 28. The bolt 30 is carried by the plunger rod 7 which carries at its outer end the piston cap 31 and a socket 32 for the universal ball 33 attached to the con- 90 95

necting rod 34. The connecting rod 34 is screw threaded at its other end to engage in the threaded socket 35 on the movable member 36 of the cross head 37. Bolts 38 extend 5 through both the cross head 37 and its movable member 36, the heads 39 of the bolt being disposed against the member 36. The nuts 40 of the bolts are spaced from the cross head 37 and between the nuts 40 and the cross 10 head 37 are wound coil springs 41. The nuts 40 are useful in adjusting the tension of the coil springs 41.

The crank is shown at 42 as having set screws 43 for securing therein the shaft 44 15 of the bell. This crank 42 carries a pin 45 for extending through the cross head 37 to which it is affixed as by a cotter pin 46 or other appropriate device.

In the use of the invention the parts are 20 initially, as shown in Figure 2, with the bell at a state of rest. The valve 13 is shown to be held open by the valve rod 22 engaging the stem 14. When the operator turns on the compressed air, such air will flow past 25 the valve 13 into the inlet 17 causing the piston or plunger 6 to move toward the right. During this movement the eye 29' of the bolt 30 will slide over the threaded portion 30 of the valve rod 22 and will finally strike the adjusting nut 28 and shift the valve rod 22 out of engagement with the valve stem 14, thus permitting the coil spring 18 to close the valve 13 against its seat 12 and cut off the further intake of the compressed air. How- 35 ever, the nuts 27 and 28 are so spaced on a valve rod 22 that this closing of the valve will not take place until the plunger 6 has traversed the major length of the cylinder 5. Even after the closing of the valve, the com- 40 pressed air in the cylinder will continue to move the plunger 6 toward the right and this action will take place up until the valve rod 22 is moved so that its reduced part 25 is brought opposite the exhaust ports 24, where- 45 upon the compressed air will be evacuated to the atmosphere.

The momentum acquired by the bell will carry the plunger 6 still further to the right until and after the air outlet 20 is masked 50 by the plunger 6. This air outlet 20 permits the cylinder to breathe freely at the right side of the plunger 6 so as not to permit of the formation of any partial vacuum which would interfere with the free movement back 55 and forth of the plunger 6. However, toward the end of the right stroke of the piston 6, this air vent 20 will be closed by the plunger 6 moving over same and thereafter the further movement of the piston 6 toward 60 the right will be cushioned by the entrapped air in the closed end of the cylinder 5. This will bring the bell to a cushioned stop and will prevent the plunger 6 from hammering against the closed head of the cylinder 5.

65 When the bell swings back it will carry

the plunger 6 with it and during the course of the return movement to the left, the eye 29' of the bolt 30 will encounter the opposite adjusting nut 27, thereby pushing the valve rod 22 back in the opposite direction or to the left, first closing the exhaust ports 24 and later reopening the valve 13. In this way the cycle of operation is repeated, the bell having been carried over the dead center by the force and momentum of its swing.

70 Should the momentum of the bell happen to move the piston to the end of the stroke, heavy knock of piston against cylinder wall is further avoided by means of the springs 41 of the cross head 37. These springs will take up the momentum which is left in the bell by compression of the springs and by separation of the cross head members 36 and 37.

75 It is obvious that various changes and modifications may be made in the details of construction and design of the above specifically described embodiment of this invention without departing from the spirit thereof, such changes and modifications being restricted only by the scope of the following 80 claims.

85 What is claimed is:—

1. An improved locomotive bell ringer comprising a cylinder having inlet and exhaust ports at one end portion and an air outlet at the other end portion, a plunger connected to the bell and fitted to reciprocate in said cylinder, a normally closed valve for controlling said inlet, and a valve 90 rod movable with said piston and having a reduced part for controlling the opening and closing of the exhaust port and further having an end portion for acting to open said valve only after the exhaust port is closed. 100

105 2. An improved locomotive bell ringer comprising a cylinder having inlet and exhaust ports at one end portion and an air outlet at the other end portion, a plunger coupled to the bell and mounted to reciprocate in said cylinder, a normally closed valve for controlling the inlet, a stem for said valve, a valve rod mounted to move with said plunger and having an end portion adapted to encounter the valve stem for opening the valve when the plunger approaches the inlet end of the cylinder, said valve rod also having a reduced portion for opening and closing the exhaust port. 115

120 3. An improved locomotive bell ringer comprising a cylinder having adjacent inlet and exhaust ports at one end portion thereof and an air outlet at the opposite end portion, a plunger coupled to the bell and fitted to reciprocate in said cylinder, a normally closed valve for controlling the inlet port, a valve rod having a portion for opening the valve and a second portion acting to open and close the exhaust port, and means 125 between said plunger and valve rod for mov- 130

ing the valve rod upon the end portions of the strokes of the plunger.

4. An improved locomotive bell ringer comprising a cylinder having adjacent inlet and exhaust ports at one end portion thereof and an air outlet at the opposite end portion, a plunger coupled to the bell and fitted to reciprocate in said cylinder, a normally closed valve for controlling the inlet port, 10 a valve rod having a portion for opening the valve and a second portion acting to open and close the exhaust port, means movable with said plunger and freely along said valve rod, and adjustable members on said 15 valve rod disposed to be encountered by said means for shifting the valve rod with the plunger.

In testimony whereof I affix my signature.
GUSTAVE WALTER.
